(57) **CLAIM**

The ornamental design for a table, as shown and described.

DESCRIPTION

FIG. 1 is a perspective view of a table showing my new design;

FIG. 2 is a side elevational view thereof;

FIG. 3 is an end elevational view thereof; and,

FIG. 4 is a top view thereof.

The views of the table not shown form no part of the claimed design. The separation and bracket in FIGS. 1, 2, and 3 indicate, for ease of illustration, that the precise height of the table is not claimed. The lines on the top and sides indicate surface shading.

The broken lines are for environmental purposes only and form no part of the claimed design.
